UNITED STATES PATENT OFFICE.

ALBERT NEAL, OF KOKOMO, INDIANA.

WRENCH.

Application filed March 14, 1925. Serial No. 15,700.

To all whom it may concern:

Be it known that I, ALBERT NEAL, a citizen of the United States, residing at Kokomo, in the county of Howard and State of Indiana, have invented certain new and useful Improvements in Wrenches, of which the following is a specification.

My said invention relates to a wrench and it is an object thereof to provide a device of this character which may be quickly and easily applied to a nut or bolt and quickly and easily released therefrom by a movement in the normal direction for turning the nut or bolt.

Referring to the accompanying drawings, which are made a part hereof and on which similar reference characters indicate similar parts,

Figure 1 is a plan of my device,

Figure 2, a longitudinal central section thereof,

Figure 3, a view of the various parts in position for assembling,

Figure 4, a view showing the jaws in one extreme position of movement, and

Figure 5, a view showing the jaws in the opposite extreme position.

In the drawings reference character 10 indicates a handle having fixed thereto, in any convenient manner, a pair of forks 11 and 12. In the present embodiment of the invention pins 13 are shown as extending through the handle and the forks 11 and 12. A pivot pin 14 extends through the forks in the longitudinal axis of the handle and is supported by said forks. Relatively movable jaws 15 and 16 have openings to receive a pivot pin 14, the jaw 15 having a slot at 17 in which a block 18 is slidably movable, the slot being somewhat longer than the block to provide a limited opportunity for movement of the jaw in the direction of the length of the slot.

The jaw 16 has a circular opening 19 to receive an eccentric or bearing element 20 in the form of a circle disposed on the inner face of the fork 12 and extending out beyond the face thereof, said eccentric 20 having an opening through which the pin 14 passes. A pin 26 serves to secure the eccentric against movement about the pin 14.

Guiding means are provided on the respective jaws, said means comprising opposed ledges 21 and 22 on each jaw between which a reduced portion 23 on the

other jaw is slidably engaged. These parts are similar on opposite sides of the wrench as will be understood from the drawings and insure proper relative positions of the respective jaws. The movable jaws are also reduced in thickness at each side as will be seen in Fig. 2 at 24 so as to provide ledges 25 overhanging the rounded ends of forks 11 and 12. These ledges in the extreme positions of the jaws rest against the flat sides of said forks and limit their swinging movement about pivot 14.

The operation of the wrench will be obvious upon consideration of the three positions shown in Figures 1, 4 and 5. The wrench may be turned to the position of Fig. 4 to open the jaws widely, after which by turning the handle in a counterclockwise direction, the jaws being in engagement with an object to be turned such as a nut or bolt, the enforced rotation of the eccentric or bearing element 20 due to its connection with fork 12 will move jaw 16 toward jaw 15 into the position shown in Fig. 1 and further movement of the handle in the same direction will move the jaw 16 further toward the jaw 15 into the extreme position of Fig. 5 when the jaws are brought as close together as possible with the construction illustrated. Turning the handle in a clockwise direction will now force the jaw 16 away from the jaw 15 successively into the positions shown in Figs. 1 and 4.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. A wrench comprising a bifurcated handle, a pair of jaws between the forks of the handle, a connection between one of said jaws and the adjacent fork of the handle comprising a bearing element in the form of a circle on one of the members, an opening in the form of a circle in the other of the members for the reception of the circular bearing element, the other of said jaws having a slot, and a pin arranged eccentrically of said circular bearing ele-

100

110

ment and extending through the slot in the last mentioned jaw, substantially as set forth.

- 5 2. A wrench comprising a bifurcated handle, a pair of jaws between the forks of the handle, one of said jaws having an opening and the other jaw having a slot, a pin connecting said jaws, a circular bearing element mounted eccentrically of said pin and secured on the inner face of one of said forks said bearing element fitting in the opening in one of said jaws, and a block on said pin 10 slideable in the slot in the other jaw, substantially as set forth.
- 15 3. A wrench comprising a handle, a pair of forks on said handle, a circular bearing element mounted on one side of a fork and extending out beyond one face thereof, a jaw having a circular opening fitting on said bearing element, a pin extending at right 20

angles from and mounted eccentrically of said circular bearing element in the longitudinal axis of said handle on the side of the bearing element remote from said handle, and a second jaw having a longitudinally disposed slot for the reception of said pin whereby when the handle is rotated with the circular bearing element turning in one jaw the pin mounted eccentrically of the bearing element will be moved transversely of said jaw and will carry the second jaw thereby causing the jaws to move toward and from each other, substantially as set forth.

25 In witness whereof, I have hereunto set my hand and seal at Indianapolis, Indiana this 12th day of March, A. D. nineteen hundred and twenty-five.

30 ALBERT NEAL. [L. S.]
